UNITED STATES PATENT OFFICE.

ALFRED WELLS CASE, OF HIGHLAND PARK, CONNECTICUT.

PRESSURE-BLOWER.

SPECIFICATION forming part of Letters Patent No. 718,693, dated January 20, 1903.

Application filed January 20, 1902. Serial No. 90,480. (No model.)

To all whom it may concern:

Be it known that I, ALFRED WELLS CASE, a citizen of the United States, residing at Highland Park, in the county of Hartford and State 5 of Connecticut, have invented certain new and useful Improvements in Pressure-Blowers, of which the following is a specification.

This invention relates to a fan-blower which is constructed to produce a greater pressure 10 of air than can be produced by the ordinary fan-blower.

The object is the construction of a blower which is simple and cheap, which will operate with little power, and which will cause a flow 15 of a considerable volume of air under more pressure than can be obtained with the ordinary fan-blower.

The blower that is illustrated as embodying the invention has a cylindrical shell with 20 a central transverse partition that separates the interior of the shell into two chambers. The partition is mounted upon the shaft, and in one chamber are the fan-blades, openings being made through the partition in front of 25 the outer ends of the blades, so that air accumulating at the outer ends of the blades may flow through the openings into the other chamber and from thence into the outlet-pipe.

Figure 1 of the accompanying drawings 30 shows a diametrical section of an improved blower mounted upon a shaft. Fig. 2 shows a face view of the blower looking in the direction indicated by the arrow 2. Fig. 3 shows a face view looking in the direction indicated by the arrow 3, and Fig. 4 shows a transverse section on the plane indicated by the broken line of Fig. 1 looking in the direction of the arrow 4.

The shaft 5 is supported by bearings of 40 common form in ordinary standards 6. The shell which is borne by and rotates with the shaft is formed of thin metal with a peripheral band 7 and a head 8, fastened to one side, and a head 9, fastened to the other side. A 45 partition 10, fastened to the shaft by flanges 11 and to the peripheral band, extends across the interior of the shell and divides the space into two chambers 12 and 13. An opening 14 is made through the head 8 for the inflow 50 of air, and an opening 15 is made through the head 9 for the outflow of air. A pipe 17 for conducting away air from the chamber 13 is

attached to the head 9 about the outlet-opening and supported in any common manner.

The fan-blades 18 are located in the chamber 55 12 between the partition 10 and the head 8. These blades are preferably arranged about tangential to the hub of the supporting-flange, as illustrated in Fig. 4.

An opening 19 is made through the partition 60 in front of the outer end of each fan-blade.

When the blower is rotated, the fan-blades collect air and cause it to be thrown toward their outer ends. This accumulates air under some pressure in the chamber 12 at the 65 outer end of the blades, which air escapes through the openings into the other chamber, from which it flows away through the discharge-pipe to the place of use. 70

I claim as my invention—

1. A pressure-blower consisting of a rotatable cylindrical shell with a central inlet-opening through one end and a central outlet-opening through the other end, a partition 75 extending parallel with the ends and dividing the interior of the shell into two cylindrical chambers, fan-blades arranged in one of the chambers, and an opening through the partition in front of the outer end of each 80 blade, substantially as specified.

2. A pressure-blower consisting of a rotatable cylindrical shell with a central inlet-opening through one end and a central outlet-opening through the other end, a partition 85 extending parallel with the ends and dividing the interior of the shell into two cylindrical chambers, fan-blades arranged in one of the chambers, and openings through the partition from the chamber in which the fan-blades are located into the other chamber, 90 substantially as specified.

3. A pressure-blower consisting of a rotatable cylindrical shell having two cylindrical chambers with a central inlet-opening through 95 one end into one chamber, and a central outlet-opening through the other end from the other chamber, with fan-blades arranged in the inlet-chamber, substantially as specified.

4. A pressure-blower consisting of two rotatable cylindrical chambers arranged end to end and supported on the same shaft with communication from one chamber to the other near their peripheries, a central inlet-opening 100.

through one end, a central outlet-opening through the other end, and fan-blades located in the chamber having the inlet-opening, substantially as specified.

5 5. A pressure-blower consisting of a rotatable cylindrical shell with a central inlet-opening through one end and a central outlet-opening through the other end, a partition extending parallel with the ends and dividing the interior of the shell into two cylin-

drical chambers, fan-blades extending tangentially from the inlet-opening to the periphery from wall to wall of one of the chambers, and openings through the partition between the blades, substantially as specified. 15

ALFRED WELLS CASE.
